UNITED STATES PATENT OFFICE.

MARK BEADLE, OF CLIMAX, MICHIGAN.

WINDMILL-COUPING.

SPECIFICATION forming part of Letters Patent No. 593,041, dated November 2, 1897.

Application filed September 5, 1896. Serial No. 605,036. (No model.)

To all whom it may concern:

Be it known that I, MARK BEADLE, a citizen of the United States, residing at the village of Climax, in the county of Kalamazoo 5 and State of Michigan, have invented a certain new and useful Windmill Coupling Device, of which the following is a specification.

My invention relates to coupling devices, and more particularly to coupling devices for 10 windmills and pumps. As heretofore constructed coupling devices of this character have been awkward to manipulate for the reason that the pump-handle and the windmill pump-rod were manipulated entirely separate, and if there was not a period at which they were both coupled to the piston-rod of the pump at the same time the piston-rod was likely to drop into the well and cause no little annoyance in its removal. An unnecessary 15 amount of time is also consumed in the manipulation of the device.

The objects of this invention are to provide a device which shall be to a large extent automatic in its operation, which requires very 20 little skill to manipulate, and which in coupling or uncoupling releases or engages the pump-handle or the pump-rod of the windmill at the same time it releases or engages the opposite part.

Further objects will appear definitely in 25 the detailed description.

I accomplish these objects of my invention by the devices and means described in the 30 following specification and illustrated in the accompanying drawings, in which—

Figure 1 is a front elevation of the top of the pump and the lower portion of a pump-rod of a windmill with one of my improved 35 coupling devices in place. Fig. 2 is a side elevation of the same. Fig. 3 is an enlarged detailed sectional view on line 3 3 of Fig. 2, showing the coupling-pin through the pump-rod. Fig. 4 is an enlarged detail transverse sectional view on line 4 4 of Fig. 2. Fig. 5 is 40 an enlarged detail transverse sectional view on line 5 5 of Figs. 1 and 2. Fig. 6 is an enlarged detail transverse sectional view on line 6 6 of Fig. 2. Fig. 7 is an enlarged detail sectional view on line 7 7 of Fig. 3. Fig. 8 is an 45 enlarged detail sectional view on the same line as the view in Fig. 3, showing the coupling-pin withdrawn and locked in place by the

key. Fig. 9 is a detail view of a modified construction of the retaining-key for the coupling-pin.

55

In the drawings all of the sectional views are taken looking in the direction of the little arrows at the end of the section-lines, and similar letters of reference refer to similar parts throughout the several views.

60

Referring to the lettered parts of the drawings, A is the pump.

B is the piston-rod of the pump, which will be referred to hereinafter as the "pump-rod."

B' is the windmill pump-rod or the rod in 65 the windmill which connects the pump-rod.

The pump-rod B extends up through a suitable guide A' on the pump and into a slide B' on the bottom of the windmill pump-rod. To the slide B', which is a portion of 70 the windmill pump-rod proper, is secured by a suitable collar C my improved coupling device. A bar in sections D D' extends down by the side of the pump-rod B and is connected to the pump-rod B by a suitable 75 clamp. The section D of the bar slides in a suitable guide in collar C. The sections of the bar D D' are secured together by a collar E, containing the key E', which clamps the two together, as clearly appears in Fig. 4. 80 A lever F is pivoted at a on the collar E and extends lengthwise of the pump-rod. Thimbles G' are movably supported toward each end of the lever F, which extends through suitable slots in the same. The thimbles are 85 also in suitable tubular guides G. The upper guide G is secured to the section D of the bar and the lower guide G is secured to the section D' of the bar.

Supported in the thimbles G' are the coupling-pins I, having spherical heads I' to retain them in the contracted ends of the thimbles. A spring M between the upper end of lever F and section D of the bar tends to throw the lever out and consequently always tends to throw the bottom end in and puts constant pressure on the lower pin I. A block K, with a strap N at the back and a plate J in front, makes up the lower collar connection. The section D' is held between 90 the plate J and block K. In a suitable recess in block K next to the pump-rod B is a movable slide or key L, (see Figs. 3, 8, and 7,) positioned to drop between the point of

pin I and the pump-rod B when the pump-handle A" is uncoupled. This through its action holds the upper coupling-pin I in place and couples the pump-rod to the windmill pump-rod. The block K is extended downwardly and outwardly to serve as a guide for the ends of the pump-rod in coupling the pump-handle in. The thickness of the key L is a little greater than the portion of the pump-handle to that side, so that merely sliding the pump-handle to place pushes the key up and releases the pin I at that point and allows it to pass through the handle and pump-rod, coupling them together. This through the connection with lever F withdraws the pin from the slide and pump-rod above and uncouples the windmill from the pump.

When it is desired to again couple the windmill and pump, the pump-rod and with it the coupling device is raised by the pump-handle till the upper pin I comes opposite the hole T in the slide B', when the pin is inserted by pressing it in, which as soon as it couples draws the lower pin from the pump-handle a" and allows the pump-handle to be withdrawn, when the key L drops and holds the pin in the disengaged position automatically. Thus it will be seen that my improved coupling for windmills is very easy to operate and it is very effective and saves all the inconvenience and annoyance heretofore experienced.

In Fig. 9 I have shown a modified form of key or lock L, which is pivoted to the block K, an arm of which is indicated by dotted lines as extending in front of the lock L. This lock has a slight advantage over the form shown in the main drawings in that it is actuated by the pump-handle in both directions and does not depend on the action of gravity at all.

Having thus described my improved coupling device, I desire to state that it can be greatly varied without departing from my invention.

The form of the pins can be changed. The guiding-bar D D' can be in a single piece. It is made in two pieces, as indicated, to accommodate the device to different sizes and styles of pumps where the holes in the pump-rod vary in their distance apart. The form of the slides can be varied also.

The form in which I have shown my device is the form preferred by me and possesses great merit.

Having thus described my invention, what I claim as new, and desire to secure by Letters Patent, is—

1. In a windmill coupling device the combination with the pump-rod B, and the windmill pump-rod B", with slide B', thereon fitted to slide together in the usual way; of a collar C, on said slide having a guideway therein; a bar made up of sections D, D', adjustably secured together fitted to said guideway; and secured to the pump-rod B; a tubular guide G, secured to each section D, D'; a thimble

G', within each guide G; a lever F pivoted at ¹⁰ _a, to the bar B, B', and extending through the thimble G', at each end; pins I, in the thimbles G', retained in place by said lever F, being fitted therethrough; a spring M, between the end of the lever F, and section D, to hold the upper end normally out; a block K, in the lower slide extended to form a guide and recessed on one side; and a key or lock L, to drop in front of the lower pin when withdrawn to hold it out all coacting as described for the purpose specified.

2. In a coupling device for windmills the combination with the pump-rod and the windmill pump-rod positioned to slide together in the usual way; a bar secured to said pump-rod; a collar on said windmill pump-rod with a guide thereon to receive said bar; a lever supported on said bar with a coupling-pin at each end the upper of which is to couple the pump-rod and the windmill-rod together and the lower of which is to couple the pump-rod and the handle together for the purpose specified.

3. In a coupling device for windmills, the combination of a pump and windmill the pump-rod and windmill pump-rod of which are positioned to slide together in the usual way; a bar secured to one of the said parts; a collar on the opposite part with a guide through which the said bar slides; a lever carried by said bar; coupling-pins on each end of said lever the upper of which serves to couple the pump-rod and windmill pump-rod and the lower of which serves to couple the handle of the pump to its rod as specified.

4. In a coupling device for windmills the combination of a pump and windmill the pump-rod and windmill pump-rod of which are positioned to strike together in the usual way; a bar secured to one of said parts and sliding on the other; a lever carried by said bar; a spring connected to said lever to throw the top of it away from said bar; coupling-pins on said lever one toward the top to couple the windmill and one toward the bottom to couple the pump-handle; a movable lock positioned in front of the lower pin when the upper pin is engaged; and the handle of the pump positioned to force the lock to one side and permit the lower pin to couple it with the pump-rod by the action of the spring which withdraws the upper pin as specified.

5. In a coupling device for windmills the combination of a pump and windmill the pump-rod and windmill pump-rod of which are positioned to slide together; a bar made up of sections D, D', adjustably secured together and supported on one of said parts and positioned to slide on the other; a lever carried by said bar; and coupling-pins at each end of said lever adjustable along the same as specified.

6. In a coupling device for windmills the combination of a pump and windmill the pump-rod and windmill pump-rod of which are positioned to slide together; a bar made

- up of sections D, D', adjustably secured together and supported on one of said parts and positioned to slide on the other; a guide G, on each section of said bar; a thimble G', in each guide G, having slots therethrough; coupling-pins I', with heads I, supported in said thimbles; and a lever F, supported by said bar and extending through the slots in said thimbles to retain the pins as specified.
- 10 7. In a coupling device for windmills the combination of a pump and windmill the pump-rod and windmill pump-rod of which are positioned to slide together in the usual way; a bar supported on one of said parts and positioned to slide on the other; a guide G, on each section of said bar; a thimble G', in each guide G, having slots therethrough; coupling-pins I, with heads I', supported by
- 15 said bar and extending through the slots in said thimbles to retain the pins as specified.
- 20 8. In a coupling device for windmills the

combination of a pump and windmill the pump-rod and windmill pump-rod of which are positioned to slide together; a lever carried by one of said parts; coupling-pins on said lever the upper of which is to couple the windmill and the lower of which is to couple the pump-handle as specified. ²⁵

9. In a coupling device for windmills the combination of a pump and windmill the pump-rod and windmill pump-rod which slide together; a pair of coupling-pins carried by one of said parts one of which is to couple the windmill and the other the pump-handle; ³⁰ and a connection between the pins coacting as specified. ³⁵

In witness whereof I have hereunto set my hand and seal in the presence of two witnesses.
